CLAIM

The ornamental design for a digital audio player as shown and described.

DESCRIPTION

1. Digital audio player

1.1 : Front perspective view

1.2 : Back perspective view

1.3 : Front

1.4 : Back

1.5 : Left

1.6 : Right

1.7 : Top

1.8 : Bottom

The broken lines shown in reproductions 1.1 to 1.8 depict portions of the digital audio player that form no part of the claimed design; the shading lines are used to show the surface of the claimed design and do not represent its surface ornamentation.

1 Claim, 8 Drawing Sheets
